FILLING FORK GRID AND CLEAVER FOR LOOMS

Filed Dec. 18, 1928

Fig.1.

UNITED STATES PATENT OFFICE

JAMES C. WRIGHT, OF CANTON, GEORGIA, ASSIGNOR TO DRAPER CORPORATION, OF HOPEDALE, MASSACHUSETTS, A CORPORATION OF MAINE

FILLING FORK GRID AND CLEAVER FOR LOOMS

Application filed December 18, 1928. Serial No. 326,800.

This invention relates to a novel form of filling fork grid for looms and the combination therewith of a clearer for removing fly, lint, yarn ends or other obstructions therefrom.

In the automatic loom it is common to provide upon the lay a grid which cooperates with a filling fork carried by the breast beam. When the pick of filling is properly laid, it extends in front of the grid and is held thereby to prevent movement of the filling fork through the grid as the lay beats up. If the pick of filling is not thus laid in front of the grid, the filling fork passes through the grid and as a result mechanism is operated to effect a change in the operation of the loom such as the stopping of the loom or replenishment of the filling carrier. Great trouble is experienced in maintaining the grid free from fly, lint, yarn ends and other obstructions collecting thereon which act to prevent the proper cooperation of the filling fork and grid.

The object of the present invention is to provide a novel form of filling fork grid in which the tines at one of their ends, and preferably at their lower ends, are free or unsupported so that any such material collecting on the grid may readily be cleared from the tines over the free ends.

A further object of the invention is to provide, in combination with such a grid having the tines with free ends, clearing mechanism acting at predetermined times thus to clear the obstructing material from the grid off over the free ends of the tines.

These and other objects and features of the invention will appear more fully from the accompanying description and drawings and will be particularly pointed out in the claims.

As the general construction and operation of the automatic loom with a grid and filling fork is well-known and familiar to those skilled in the art, it is only necessary here to illustrate and describe those parts of a loom directly concerned with a preferred form of the invention.

In the drawings:

Fig. 1 is a side elevation partially in ver-

tical cross section looking from the interior of the loom toward one side frame thereof with a preferred form of the present invention embodied therein.

Fig. 2 is a top plan view partially broken away and partially in horizontal cross section of a preferred form of cooperating grid and clearer.

Fig. 3 is a perspective view of a preferred form of the grid embodying the invention.

One of the side frames 1 of an automatic loom is shown, together with the transversely extending breast beam 2, transversely extending girders 3 such as commonly employed for supporting a warp stop motion,

transversely extending cam shaft 4 and the usual lay 5 carried by the lay swords 6 and swinging forward and rearward about the usual lay rock shaft, not shown, at the bottom of the loom. A usual type of filling fork 7 with its slide 8 mounted on the breast beam is shown. This filling fork swings freely on the pivot 9. A cam 10 on the cam shaft 4 acting against a cam follower

11 on the end of a weft hammer 12 fulcrumed at 13 acts to rock the weft hammer at every other pick, or when the shuttle is boxed at the side of the loom at which the filling fork is located. When, therefore, the lay beats up with a pick of filling properly laid by the shuttle boxed at this side of the loom, the filling will swing the fork 7 on its pivot 9, releasing its forward end from the hook 14 pivoted to the weft hammer

and no change takes place. But if the filling is absent from in front of the filling fork, there will be no movement of the filling fork and it will remain in engagement with the hook 14 and the weft hammer will move the fork slide forward, effecting the desired

change in the operation of the loom.

A grid mounted on the lay is the means provided for holding the filling in position for cooperation with the filling fork and in this invention a novel form of such grid is presented. The grid shown generally at 15 in Fig. 1 has its body portion extending vertically in front of the path of the filling fork and is rigidly secured to the lay adjacent the inner end of the usual shuttle

box so that it stands about in the same plane as the usual reed. This grid is shown separately in Figs. 2 and 3 and in this invention comprises a bar 16 extending horizontally and preferably at the top of the grid. From this bar extend a plurality of tines 17, the body portions of which stand vertical or parallel with the reed. As shown, the tines first extend laterally forward at 18 from the top bar, thence in their main body portion downwardly. The important feature of construction resides in the fact that the ends of the tines opposite the top bar 16, and in the preferred case the lower ends 19 of the tines, are free or unsupported and are preferably pointed at 19 and preferably deflected or bent back to extend rearward. A suitable supporting lug 20 forms a part of the grid and is shown as an extension 20 of the outer tine 17. This lug is provided with a slot 21 by means of which the grid may be bolted in position on the lay.

It will thus be seen that any fly, lint, yarn ends or other obstruction collecting on the grid in the operation of the lay and which would interfere with the proper cooperation of the grid with the filling fork may readily be slid or cleared off from the grid over the free or unsupported ends of the tines. Broadly considered, this clearing action may be performed by any suitable means such as a pneumatic device or air hose which could be directed against the grid to remove the obstructing material down along and off the free ends of the tines; such as a brush or other simple mechanical element in the hand of the operative; or a mechanical means provided for the purpose.

A further feature of the invention resides 40 in a combination with the novel grid of this invention of a mechanical clearer thus acting to clear the obstructing material off over the free ends of the tines.

In the preferred form of construction illustrated, a metal standard 22, made in two parts longitudinally adjustable by means of the slot 23 and bolt 24 construction, is clamped to the weft hammer 12 adjacent the follower 11 so that the standard is positioned 50 substantially vertical directly in the rear of the lay when in its rear position. Near its upper end this standard is loosely guided in a bracket 25 secured by bolts 26 to some rigid portion of the loom such as one of the girders 3. The standard 22 is bent forward at its upper end and has secured thereto by a bolt 27 a horizontally extending base 28 of a brush having long flexible bristles 29. The parts are so positioned that when 60 the lay is in its rear position, as shown in Fig. 1, the bristles will penetrate between the tines of the grid 15 and the cam 10 will insure that in every series of two picks at least the brush will engage the entire surface 65 face of the grid. With the parts as shown

in Fig. 1, that is, with the lay in its rear position, it will be seen that as the lay swings forward to beat up, the grid moves on a circular arc so that there is a slight relative vertical movement between the grid 70 and the brush, the brush moving downward relatively to the grid and that there is also a separating movement as the grid moves away from the brush, and that these relative movements are accentuated by the movement imparted to the weft hammer and consequently to the brush by the cam 10. The result is that the brush penetrating the grid engages any fly, lint, yarn ends, or other obstruction collecting on the grid and draws 80 this material down the tines and off over the free or unsupported rearwardly extending pointed ends. This cooperative action involving the novel construction of tines having the free or unsupported ends insures that the grid is constantly kept clear and free of all obstructing material so that perfect cooperative action is maintained between the filling fork and the grid. 90

The construction may readily be embodied in existing looms merely by substituting the new form of grid for the forms heretofore employed and by mounting the clearer brush and its supporting standard and bracket 95 upon the proper parts of the loom.

Having thus described the invention, what is claimed as new, and desired to be secured by Letters Patent, is:

1. A filling fork grid for looms comprising a top bar and a plurality of parallel spaced tines rigid with and depending from the top bar with their lower ends free to permit any fly, lint, yarn ends or other obstruction collecting on the tines to be cleared from the tines over their free ends and means for supporting the grid with the top bar and tines in fixed position on the loom. 100

2. A filling fork grid for looms comprising a top bar and a plurality of parallel spaced tines depending from the top bar with their lower ends free and deflected rearward to permit any fly, lint, yarn ends or other obstruction collecting on the tines to be cleared from the tines over their free ends. 110

3. A filling fork grid for looms comprising a top bar and a plurality of parallel spaced tines depending from the top bar with their lower ends free and pointed and extended rearward to permit any fly, lint, yarn ends or other obstruction collecting on the tines to be cleared from the tines over their free ends. 120

4. A filling fork grid for looms having a transverse bar and a plurality of parallel spaced tines rigid with and extending from the bar with their ends opposite the bar free to permit any fly, lint, yarn ends or other obstruction collecting on the tines to 130

be cleared from the tines over the free ends and means for supporting the grid with the transverse bar and tines in fixed position on the loom.

5 5. The combination in a loom of a filling fork grid comprising a top bar and a plurality of parallel spaced tines depending from the top bar with their lower ends free and deflected rearward, clearing means acting to engage the grid from the rear and means acting to give a downward and rearward movement of the clearing means relatively to the grid to remove fly, lint, etc., collecting on the tines down off from the 10 free ends of the tines.

In testimony whereof, I have signed my name to this specification.

JAMES C. WRIGHT.
